UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

1,425,293.

Specification of Letters Patent. Patented Aug. 8, 1922.

Application filed November 18, 1918. Serial No. 262,939.

To all whom it may concern:

Be it known that I, JESSE A. B. SMITH, a citizen of the United States, residing in Stamford, in the county of Fairfield and State of Connecticut, have invented certain new and useful Improvements in Typewriting Machines, of which the following is a specification.

This invention relates principally to typewriting machines of those of the class disclosed in the patent to Wernery and Smith, No. 1,132,055, in which superposed plies of work-web are led to the typewriter carriage from the rear and passed forwardly around the platen and upwardly to receive the type impressions. In such machines, the platen is displaceable upwardly after the completion of the typing of each form on the web, to permit the plies of web to be straightened, so that the carbon sheets which interleave the plies may be retracted for fresh use. The typed form is then severed from the web.

In some cases, it is desired to retain in the machine a condensed record sheet, to receive carbon impressions of a succession of bills or forms that are typed upon the main webs; the forms being usually severed from the web one by one after being typed.

The object of this invention is to improve the means for controlling the record sheet, which usually lies next to the platen, being advanced with the web plies during line-feeding operations, but remaining stationary during the pulling forward of the web preparatory to tearing off the typed form therefrom.

According to the present improvements, the platen is automatically rotated one, two, or three line-spaces, during the upward displacement of the platen for permitting the webs to be straightened out. Since this platen-displacing operation occurs once for every form that is typed upon the web, it results that the record sheet, which remains in contact with the platen, is automatically advanced thereby, independently of the plies of web, once for every form that is severed from the web. The record sheet is held against the platen by special feed-rolls, which remain effective as the platen rises, to insure the advance of the record sheet with the platen at this time.

These rolls are preferably placed one on

each end of the platen, to run upon the side margins of the record sheet, which for this purpose, may be made wider than the plies of web. These rolls may be placed at the front of the platen, so as to bite the record sheet nearly at the printing line, so that about all of the record sheet may be used, avoiding the necessity of providing excessive blank margins at either top or bottom thereof.

Another feature of this invention is an improvement in the manner of mounting such rolls. They are carried upon the forward ends of arms which extend forwardly from a horizontal rod, which extends along the back of the carriage and is mounted thereon. These arms may slide along the rod to accommodate sheets of different widths. Moreover, these special rolls may be released from the platen whenever desired, this being accomplished by means of a key mounted upon the carriage and connected to release the roll-carrying arms wherever they are adjusted along the rod.

While the platen is displaced, a connection between the ordinary line-space wheel and the revolute platen is maintained by a train of gearing, such a train being shown in said Wernery and Smith patent. According to the present invention, the line-spacing wheels are driven automatically during the rise of the platen, and thereby revolve the same; and the usual spring detent, riding over the teeth of the line-space ratchet wheel, serves to hold the platen at the position to which it is rotated by the line-space mechanism. The line-space mechanism of the Underwood machine usually comprises a slide which carries a pawl, and said pawl engages the line-space ratchet wheel whenever the slide is pushed backwardly, this usually being accomplished by a lever or handle. In carrying out the present improvements, the platen frame is provided with an arm which engages said slide or a pin thereon, and drives the slide rearwardly for effecting the line-space movement.

Said driving arm, which is connected to the platen frame, may be so proportioned as to effect a complete driving stroke of said pawl-carrying slide, the same as done by the usually manually-operated lever, and hence the line-spacing pawl may remain

normally out of engagement with the ratchet wheel, as before, and the usual line-space regulator may be employed which controls the duration of the engagement of the driving pawl and the ratchet wheel, and therefore controls the extent of line-spacing movement of the platen. Thus, the extent of automatic advance of the record sheet may be regulated.

10 Other features and advantages will hereinafter appear.

In the accompanying drawings,

Figure 1 is a perspective front view of an Underwood typewriting machine illustrating the class disclosed in said Wernery and Smith patent, and showing my improvements in one form, some of the parts being in normal positions.

Figure 2 is a sectional side elevation of 20 the carriage of said Underwood machine, showing parts in normal positions.

Figure 3 is a fragmentary view to illustrate the manner of releasing the rolls which hold the record sheet upon the platen 25 of the typewriting machine.

Figure 4 is a view showing the platen near the final stage of its upward displacement, and illustrating the manner in which the line-spacing rotating movement of the 30 platen is begun at this stage.

Figure 5 is a view showing the parts seen in Figure 2, but illustrating the upward displacement of the platen as completed, and the line-space operation also as completed.

35 The plies of web 10 are led in at the rear of the machine, and passed forwardly over a traveling slide 11 which has blades 12 to carry sheets 13 of carbon in between the 40 plies of web, and which may slide forwardly with the plies, and also be slid rearwardly, independently of the plies, to feed the carbons to fresh positions relatively to the webs. The plies with the interleaved carbons pass downwardly around the revoluble platen 14 and between the same and the usual releasable bottom feed rolls 15, and then upwardly in front of the platen to a position to receive the impression of the types 16.

50 A separate sheet 17 is placed next to the platen and is faced with a special carbon sheet 18 which may be carried by said slide, the special sheet receiving the carbon impressions of a succession of forms which are typed and then torn off from the web plies.

55 After the completion of the typing of a form, the platen is raised or displaced upwardly, to permit the plies to be straightened out preparatory to sliding back the carbon-carrier, Figure 5. The platen for these purposes is mounted upon a swinging frame 19, which is hinged at 20 to a main platen frame or carriage 21, so that 60 the platen may be swung upwardly.

Connection between the platen and the usual line-space wheel 22 and platen-rotating knob 23 is maintained by means of a train of gearing comprising gears 24, 25, one rigidly connected to the line-space 70 wheel, and the other rigidly connected to the platen 14, said gears both meshing with a broad pinion 26, which is mounted upon the main platen frame concentrically with the hinge 20, so that connection between the 75 line-space wheel and the platen is always maintained.

Upon the swinging platen frame 19 is fixed, at one end, a driving arm or tappet 27, which at the upward swinging of the 80 platen engages a pin 28 which projects from a line-spacing slide 29 usually provided upon the Underwood typewriter. By this means, said slide is given a full rearward stroke, the same as it receives from the 85 manually-operated lever 30. Said slide is operable either by said driving arm or said operating lever. Upon said slide 29 is the usual pawl 31 for engaging the teeth of the line-space wheel 22. Other devices are 90 usually found upon this portion of said Underwood machine, including a stop to prevent overthrow of the pawl, and means to regulate the extent to which the line-space wheel is rotated by the pawl, said 95 regulating means including the handle 32, which is usually adjustable to three positions for single, double and triple line-spacing. The extent of the movement of the slide 29 is the same for all three positions of the line-space regulator 32, and hence the extent to which the platen is automatically rotated at the elevation thereof may be determined by the adjustment of this regulator 32; the slide 100 29 being given a full stroke in every instance.

When the latch 33 is released that usually holds down the platen-swinging frame 19, and said frame is swung up, an independent 110 regulatable rotation of the platen is automatically effected. When the platen is dropped back to printing position, the line-spacing slide 29 is returned by its usual spring 34, and the parts resume normal 115 positions with the latch 33 resuming its function of holding down the platen frame 19.

This automatic line-feeding of the platen serves to advance the record sheet 17 independently of the webs 10, the side borders of said record sheet being held against the platen by means of special rolls 35, which escape the plies of web 10, and grip the record sheet 17 at points near the print- 125 ing line, avoiding waste of paper.

While other kinds of rolls 35 may be employed and while they may be otherwise placed, it is preferred to place them upon the forward ends of arms 36, which ex- 130

tend forwardly over the top of the platen and are carried upon a horizontal rod 37 which extends above the platen and is supported in ears 38 provided upon a paper shelf 39, which usually extends upwardly from the delivery side of the platen. These arms 36 are preferably adjustable along said rod to accommodate different widths of record sheets, or different positions of the same lengthwise of the platen. To permit the rolls to be released from the platen, the arms at the rear ends are pivoted at 40 upon mounts 41 which slide upon the rod 37 and are splined thereto. Springs 42 connect the arms with the mounts, so that the rolls may always bear as firmly as required against the platen.

For releasing the rolls 35, there is provided a special release key 43 upon the end 20 of an arm 44, which is mounted upon a horizontal rock-shaft 45 which extends along the paper shelf 39 and is mounted in the ears 38. Upon this shaft 45 are splined releasing cams 46 which engage the roll-carrying 25 arms 36 to lift the same upon the operation of the release key 43; the parts being so formed that the roll-carrying arms will be locked in released positions, as at Figure 3, by the arm 44 which is arrested by a stop 30 43^a on the ear 38. Upon lifting the key, the springs 42 will restore the rolls 35 to engagement with the platen 14. The releasing cams 46 are forked at 47 to engage the arms 36, so as to be carried along there- 35 by when the arms are adjusted along the rod 37, and hence the release key 43 will serve to release the rolls wherever the arms are adjusted along the platen.

Variations may be resorted to within the 40 scope of the invention, and portions of the improvements may be used without others.

Having thus described my invention, I claim:

1. The combination with a revolute 45 platen, of line-spacing mechanism therefor, mechanism for displacing the platen from printing position, and means operable by said displacing mechanism for line-spacing the platen.

2. The combination with a revolute 50 platen displaceable from printing position, of regulatable line-spacing mechanism connected to operate at the platen-displacing operation.

3. In a typewriting machine, the combination 55 with a revolute platen and line-spacing mechanism therefor, of a displaceable frame in which said platen is mounted for movement into and out of printing position, and means connected to said frame to operate said line-spacing mechanism to rotate the platen at the displacement of the frame.

4. In a typewriting machine, the combination 60 with a revolute platen and a dis-

placeable frame in which it is mounted, of a main frame upon which said displaceable frame is mounted, line-spacing mechanism upon the main frame, a train of gearing between said line-spacing mechanism and the platen, and means connected to the displaceable frame for operating said line-spacing mechanism at the displacement of the platen. 70

5. In a typewriting machine, the combination 75 with a revolute platen and a displaceable frame in which it is mounted, of a main frame upon which said displaceable frame is mounted, line-spacing mechanism upon the main frame, a train of gearing 80 between said line-spacing mechanism and the platen, and an arm or tappet upon said displaceable frame to engage a part of the line-spacing mechanism upon the main frame to operate the same. 85

6. The combination with a frame, of a line-spacing mechanism mounted thereon, a revolute platen displaceably mounted upon said frame for movement into and out of printing position, means connecting said 90 platen permanently to said line-spacing mechanism, and means effective at the platen-displacing mechanism for operating said line-spacing mechanism.

7. The combination with a frame, of a 95 line-spacing mechanism mounted thereon, a revolute platen displaceably mounted upon said frame for movement into and out of printing position, means connecting said platen permanently to said line-spacing mechanism, means effective at the platen-displacing mechanism for operating said line-spacing mechanism, and a manually operable device upon said frame for operating said line-spacing mechanism at 100 will. 105

8. The combination of a line-space wheel, a driving pawl therefor, a part to drive said pawl, a revolute platen mounted for displacement relatively to said line-space 110 wheel, a train of gearing to maintain connection between the line-space wheel and platen, and means effective at the displacement of the platen for operating said part to turn the line-space wheel and platen. 115

9. The combination of a line-space wheel, a driving pawl therefor, a part to drive said pawl, a revolute platen mounted for displacement relatively to said line-space 120 wheel, a train of gearing to maintain connection between the line-space wheel and platen, means effective at the displacement of the platen for operating said part to turn the line-space wheel and platen, and a line-space lever to operate said part. 125

10. The combination of a line-space wheel, a driving pawl therefor, a part to drive said pawl, a revolute platen mounted for displacement relatively to said line-space 130 wheel, a train of gearing to maintain con-

nection between the line-space wheel and platen, means effective at the displacement of the platen for operating said part to turn the line-space wheel and platen, and 5 regulatable means for varying the extent of rotation imparted to the platen at the upward displacement thereof.

11. In a typewriting machine, the combination with a revoluble platen, of line-spacing mechanism therefor, mechanism for displacing the platen from printing position, means operable by said displacing mechanism for line-spacing the platen, and pressure devices bearing upon the platen to 10 hold a work-sheet thereon while the platen is being displaced and line-spaced, thereby to line-feed said work-sheet.

12. In a typewriting machine, the combination with a revoluble platen displaceable from printing position, of pressure devices bearing upon the platen at the printing position only and releasable therefrom by the displacement of the platen to release a work-sheet held thereby, other 20 pressure devices bearing upon the platen adjacent to its ends to engage the margins of a wider work-sheet thereon during and after the displacement of the platen, line-spacing mechanism connected to operate 25 at the platen-displacing operation for thereby line-feeding said wider work-sheet, and a manually-operable device for operating said line-spacing mechanism at will.

13. In a typewriting machine, in combination, a revoluble platen, line-spacing mechanism therefor, a displaceable frame in which said platen is mounted for movement into and out of printing position, means connecting said platen permanently to said line-spacing mechanism, means connected to said frame to operate said line-spacing mechanism to rotate the platen at the displacement of the frame, and pressure devices carried by said frame to hold a work-sheet on the 45 platen during and after the displacement of the platen.

14. In a typewriting machine, the combination with a revoluble platen and a displaceable frame in which it is mounted, of 50 a main frame upon which said displaceable frame is mounted, line-spacing mechanism upon the main frame, means connecting said platen permanently to said line-spacing mechanism, means connected to the displaceable frame for operating said line-spacing mechanism at the displacement of the platen, a manually-operable device upon 55 said main frame for operating said line-spacing mechanism at will, a set of feed-rolls carried by said main frame for pressing work-sheets against the platen at the printing position and away from which said platen is displaceable, and another set of feed-rollers carried by said displaceable 60 frame to co-operate with the platen during 65

and after its displacement for pressing the side margins of a wider work-sheet against the platen.

15. In a typewriting machine, the combination with a revoluble platen and feed-rolls to run on the bottom thereof, of line-spacing mechanism therefor, work-controlling mechanism including means for displacing the platen upwardly from printing position away from said rolls, and means operable by said displacing means for line-spacing the platen, said work-controlling mechanism also comprising a paper shelf at the delivery side of the platen and displaceable therewith, a rod displaceable with the platen 70 and extending along the upper portion of said paper shelf, and arms supported by and adjustable along said rod and extending forwardly and downwardly over said paper shelf and displaceable with said platen, and 75 having means to press a work-sheet against the platen to co-operate therewith to feed the work-sheet while the platen is being line-spaced during the time that it is out of co-operation with the bottom feed-rolls. 80

16. In a typewriting machine, the combination with a revoluble platen and feed-rolls to run on the bottom thereof, of line-spacing mechanism therefor, work-controlling mechanism including means for displacing the platen upwardly from printing position away from said rolls, and means operable by said displacing means for line-spacing the platen, said work-controlling mechanism also comprising a paper shelf at the delivery side of the platen and displaceable therewith, and arms adjustable along the platen and extending over said paper shelf and displaceable with said platen, and having 90 means to press a work-sheet against the platen to co-operate therewith to feed the work-sheet while the platen is being line-spaced during the time that it is out of co-operation with the bottom feed-rolls. 95

17. In a typewriting machine, the combination with a revoluble platen and feed-rolls to run on the bottom thereof, of line-spacing mechanism to actuate the platen, mechanism for displacing the platen upwardly from printing position and away from said feed-rolls, means operable by said displacing mechanism for line-spacing the platen, and means displaceable with said platen for pressing a work-sheet against the 100 platen to cooperate therewith to feed the work-sheet while the platen is being line-spaced during the time that it is out of co-operation with the bottom feed-rolls. 105

18. In a typewriting machine, the combination with a revoluble platen and feed-rolls to run on the bottom thereof, of mechanism for line-spacing the platen, and work-controlling mechanism including means for displacing the platen upwardly from print- 110 115 120 125 130

ing position and away from said feed-rolls and for actuating said line-spacing mechanism, a paper shelf at the delivery side of the platen and displaceable therewith, a 5 rod displaceable with and extending along the upper portion of said paper shelf, arms supported upon and adjustable along said rod and extending downwardly over said paper shelf, and having means for pressing the margins of a wide work-sheet against the platen during and after its displacement, to co-operate therewith to feed the work-sheet while the platen is being line-spaced during the time it is out of co-operation with the bottom feed-rolls, a second rod 10 substantially parallel to the first and displaceable therewith, a release-key connected to said second rod, cams splined to said second rod for releasing said arms and means connecting said cams to said arms to be adjustable therewith.

19. In a typewriting machine, the combination with a revoluble platen and feed-rolls to run on the bottom thereof, of line-spacing mechanism to actuate the platen, mechanism for displacing the platen upwardly from printing position and away from said feed-rolls, means operable by said displacing mechanism for line-spacing the platen, 25 and arms displaceable with said platen and having means to engage only the side margins of a work-sheet, to press it against the platen to co-operate therewith to feed the work-sheet while the platen is being line-spaced during the time that it is out of co-operation with the bottom feed rolls.

20. In a typewriting machine, in combination, a revoluble platen, feed-rolls to run on the bottom thereof, line-spacing mechanism for the platen, a displaceable frame in which said platen is mounted for movement into and out of printing position, means connected to said frame to operate said line-spacing mechanism to rotate the platen at the displacement of the frame, a paper shelf mounted on said frame at the delivery side of the platen, a rod carried by said frame and extending along the upper end of said paper shelf, and arms supported on and adjustable along said rod and extending downwardly over said paper shelf and having means to press a work-sheet against the platen to co-operate therewith to feed the work-sheet while the platen is being displaced during the time it is out of co-operation with the bottom feed-rolls.

21. In a typewriting machine, in combination, a revoluble platen, feed-rolls to run on the bottom thereof, line-spacing mechanism for the platen, a displaceable frame in which said platen is mounted for movement into and out of printing position, means connected to said frame to operate said line-spacing mechanism to rotate the platen at

the displacement of the frame, a paper shelf mounted on said frame at the delivery side of the platen, a rod carried by said frame at the rear of the paper shelf, mounts 70 slideable along said rod and splined thereto, and spring-pressed arms pivoted upon said mounts and extending forwardly over said paper shelf and carrying at their forward ends feed-rolls to run upon the platen, to co-operate therewith to feed a work-sheet 75 while the platen is being line-spaced during the time that it is out of co-operation with the bottom feed-rolls.

22. In a typewriting machine, in combination, a revoluble platen, feed-rolls to run on 80 the bottom of the platen, line-spacing mechanism for the platen, a displaceable frame in which said platen is mounted for movement into and out of printing position, means connected to said frame to operate 85 said line-spacing mechanism to rotate the platen at the displacement of the frame, a paper shelf mounted on said frame at the delivery side of the platen, a rod carried by said frame at the rear of the paper shelf, 90 mounts slideable along said rod and splined thereto, spring-pressed arms pivoted upon said mounts and extending forwardly over said paper shelf and carrying at their forward ends feed-rolls to run upon the platen, 95 to co-operate therewith to feed a work-sheet while the platen is being displaced during the time it is out of co-operation with the bottom feed-rolls, and means to release said arms concurrently from the 100 platen and mechanically lock them in released position.

23. In a typewriting machine, in combination, a revoluble platen, feed-rolls to run on the bottom of the platen, line-spacing 105 mechanism for the platen, a displaceable frame in which said platen is mounted for movement into and out of printing position, means connected to said frame to operate said line-spacing mechanism to rotate the 110 platen at the displacement of the frame, a paper shelf mounted on said frame at the delivery side of the platen, a rod carried by said frame at the rear of the paper shelf, mounts slideable along said rod and splined 115 thereto, spring-pressed arms pivoted upon said mounts and extending forwardly over said paper shelf and carrying at their forward ends feed-rolls to run upon the platen, to co-operate therewith to feed a work-sheet while the platen is being displaced and the platen and bottom feed-rolls are separated, a second rod substantially parallel to the first and displaceable therewith, a release key connected to said second rod, 120 125 cams splined to said second rod for releasing said arms, and means connecting said cams to said arms to be adjustable therewith.

24. In a typewriting machine, the combi- 130

- nation with a revolute platen and a displaceable frame in which it is mounted, of a main frame upon which said displaceable frame is mounted, line-spacing mechanism 5 upon the main frame, means connecting said platen permanently to said line-spacing mechanism, means connected to the displaceable frame for operating said line-spacing mechanism to feed the platen at the displacement thereof, a set of feed-rolls carried by said main frame for pressing work-sheets including a sheet wider than the others against the platen at the printing position and away from which said platen 10 is displaceable, a paper shelf mounted upon said displaceable frame at the delivery side of the platen, a rod carried by said displaceable frame and extending along the upper end of said paper shelf, and arms supported on and adjustable along said rod and extending downwardly over said paper shelf and having at their lower ends feed-rolls to turn upon the platen to co-operate with the platen during and after its displacement 15 for pressing the side margins of the wider work-sheet against the platen, so that the wider work-sheet will be fed during the displacement of the platen away from the bottom feed-rolls and the release of the 20 wider work-sheet from the latter.
25. In a typewriting machine, the combination with a revolute platen and a displaceable frame in which it is mounted, of a main frame upon which said displaceable frame is mounted, line-spacing mechanism upon the main frame permanently connected to said line-spacing mechanism, means connected to the displaceable frame for operating said line-spacing mechanism at the displacement of the platen, a set of feed-rolls carried by said main frame for pressing work-sheets against the platen at the printing position and away from which said platen is displaceable, a paper shelf mounted upon 30 said displaceable frame at the delivery side of the platen, a rod carried by said displaceable frame at the rear of the paper shelf, mounts slidable along said rod and splined thereto, and spring-pressed arms pivoted 35 upon said mounts and extending forwardly over said paper shelf and carrying at their forward ends feed-rolls to run upon the platen to cooperate with the platen during and after its displacement for pressing the side margins of a wider work-sheet against the platen, so that the wider work-sheet will be fed by the platen when the latter is line-spaced during the displacement thereof away from the feed-rolls on the main frame.
40. 26. In a typewriting machine, the combination with a revolute platen and a displaceable frame in which it is mounted, of a main frame upon which said displaceable frame is mounted, line-spacing mechanism 45 upon the main frame, means connecting said platen permanently to said line-spacing mechanism, means connected to the displaceable frame for operating said line-spacing mechanism at the displacement of the platen, a set of feed-rolls carried by said main frame for pressing work-sheets against the platen at the printing position and away from which said platen is displaceable, a paper shelf mounted upon said displaceable frame at the delivery side of the platen, a rod carried by said displaceable frame at the rear of the paper shelf, mounts slidable along said rod and splined thereto, spring-pressed arms pivoted upon said mounts and extending forwardly over said paper shelf and carrying at their forward ends feed-rolls to run upon the platen to co-operate with the platen after its displacement for pressing the side margins of a wider work-sheet against the platen, so that the latter when line-spaced in its movement away from said set of feed-rolls will feed said wider work-sheet, and means for concurrently releasing said arms from the platen and for mechanically locking them in released position. 50
27. In a typewriting machine, the combination with a revolute platen and a displaceable frame in which it is mounted, of a main frame upon which said displaceable frame is mounted, line-spacing mechanism upon the main frame, means connecting said platen permanently to said line-spacing mechanism, means connected to the displaceable frame for operating said line-spacing mechanism at the displacement of the platen, a set of feed-rolls carried by said main frame for pressing work-sheets against the platen at the printing position and away from which said platen is displaceable, a paper shelf mounted upon said displaceable frame at the delivery side of the platen, a rod carried by said displaceable frame at the rear of the paper shelf, mounts slidable along said rod and splined thereto, spring-pressed arms pivoted upon said mounts and extending forwardly over said paper shelf and carrying at their forward ends feed-rolls to run upon the platen to co-operate with the platen during and after its displacement for pressing the side margins of a wider work-sheet against the platen, so that the wider work-sheet will be fed by the platen when the latter is line-spaced during its movement away from the feed-rolls on the main frame, a second rod carried by said displaceable frame substantially parallel with the first and displaceable therewith, a release key connected to said second rod, cams splined to said second rod for releasing said arms, and means connecting said cams to said arms to be adjustable therewith. 55
28. In a typewriting machine, the combination with a revolute platen and a displaceable frame in which it is mounted, of a main frame upon which said displaceable 60

- frame is mounted to swing forwardly, said main frame having a front bar, line-spacing mechanism upon the main frame, means connecting said platen permanently to said line-spacing mechanism, means connected to the displaceable frame for operating said line-spacing mechanism at the displacement of the platen, a set of feed-rolls carried by said main frame for pressing work-sheets against the platen in the printing position and away from which said platen is displaceable, a paper shelf mounted upon said displaceable frame at the delivery side of the platen, and arms supported upon said displaceable frame and extending downwardly at the front of said paper shelf in position to clear the front bar of the main frame when the displaceable frame is swung forward to displace the platen, said arms having at their lower ends feed-rolls to turn upon the platen to co-operate with the platen during and after its displacement for pressing the side margins of a wider work-sheet against the platen, so that the wider work-sheet will be fed by the platen when the latter is line-spaced during its movement away from the feed-rolls on the main frame.
29. In a typewriting machine, the combination with a revoluble platen, feed-rolls to run on the bottom thereof, and a platen-frame, of line-spacing mechanism to actuate the platen, mechanism for displacing the platen relatively to said platen-frame and upwardly from printing position and away from said feed-rolls, means operable by said displacing mechanism for line-spacing the platen, and arms adjustable longitudinally of the platen and displaceable with said platen and carrying means to press a work-sheet against the platen to co-operate therewith to feed the work-sheet while the platen is being line-spaced during the time that it is out of co-operation with the bottom feed-rolls.
30. In a typewriting machine, the combination with a revoluble platen, of line-spacing mechanism therefor, mechanism for displacing the platen from printing position, means operable by said displacing mechanism for line-spacing the platen, a paper shelf at the delivery side of the platen and displaceable therewith, and spring-pressed pivoted arms displaceable with and extending downwardly over said paper shelf and having means at their lower ends for pressing a work-sheet against the platen.
31. In a typewriting machine, the combination with a revoluble platen displaceable from printing position, of line-spacing mechanism connected to operate at the platen-displacing operation, pressure devices bearing upon the platen at the printing position only and releasable therefrom at the displacement of the platen to release a work-sheet held thereby; a paper shelf at the delivery side of the platen displaceable therewith, and spring-pressed pivoted arms displaceable with and extending downwardly over said paper shelf and having at their lower ends means for pressing the margins of a wider work-sheet against the platen during and after its displacement.
32. In a typewriting machine, in combination, a revoluble platen, line-spacing mechanism therefor, a displaceable frame in which said platen is mounted for movement into and out of printing position, means connecting said platen permanently to said line-spacing mechanism, means connected to said frame to operate said mechanism to rotate the platen at the displacement of the frame, a paper shelf mounted on said frame at the delivery side of the platen, and spring-pressed pivoted arms displaceable with and extending downward over said paper shelf and having means for pressing a work-sheet against the platen.
33. In a typewriting machine, the combination with a revoluble platen and a displaceable frame in which it is mounted, of a main frame or carriage upon which said displaceable frame is mounted, line-spacing mechanism upon the main frame, means connecting said platen permanently to said line-spacing mechanism, means connected to the displaceable frame for operating said line-spacing mechanism at the displacement of the platen, a set of feed-rolls carried by said main frame for pressing work-sheets against the platen at the printing position and away from which said platen is displaceable, a paper shelf mounted upon said displaceable frame at the delivery side of the platen, and spring-pressed pivoted arms displaceable with and extending downwardly over said paper shelf and having at their lower ends feed-rolls to turn upon the platen during and after its displacement for pressing the side margins of a wider work-sheet against the platen.
